W. T. B. ROBERTS

FASTENING INSERTING MACHINE

Filed Sept. 3, 1924

UNITED STATES PATENT OFFICE.

WILLIAM THOMAS BUCKINGHAM ROBERTS, OF LEICESTER, ENGLAND, ASSIGNOR TO
UNITED SHOE MACHINERY CORPORATION, OF PATERSON, NEW JERSEY, A COR-
PORATION OF NEW JERSEY.

FASTENING-INSERTING MACHINE.

Application filed September 3, 1924, Serial No. 735,612, and in Great Britain September 18, 1923.

This invention relates to fastening forming and inserting machines and is herein shown, by way of illustration, as embodied in a machine for severing and inserting wire slugs in the bottoms of boots and shoes of the type disclosed in United States Letters Patent No. 786,190, granted March 28, 1905, on application of Louis A. Casgrain.

Objects of the invention are to improve generally machines of this type, to provide improved cutting mechanism for the wire, and so to organize the wire feeding, the severing, and the severed-slug presenting mechanism of such a machine as to prevent injury to the machine in case of the projection of any solid object, such as a slug or a piece of a broken driver, from the throat of the machine during the return movement of the slug presenting mechanism. In prior machines either of these events is apt to result in breakage of parts.

In carrying out these objects, it is found desirable to eliminate the usual movement of translation of the throat carrier to transfer the severed slug beneath the driver, which change reduces not only the likelihood of a partially expelled slug being retained by the throat as it moves from slug driving position to slug receiving position, but also renders it easier to provide safety devices for preventing damage to the machine should the slug be retained.

One feature of the invention consists in a fastening shearing throat movable to present the fastening in inserting position, and means co-operating with said throat for feeding the fastening material thereto arranged to yield out of the path of a projecting fastening or other object brought toward it by the return movement of the throat.

Another feature of the invention consists in means for forming and inserting fastenings, means for feeding fastening material to the forming and inserting means, and means for rendering the feeding means inoperative in case the inserting means be-

comes obstructed, for example, by a fastening or broken driver.

Still another feature of the invention consists in fastening receiving means having fastening shearing and presenting movements, and mechanism operating under comparatively high power for causing comparatively slow relative movement of the dies during the severing operation and operating under lower power to move one of the dies at a higher speed during the transference of the fastening to inserting position. As shown herein, two driving mechanisms are provided which may operate in conjunction to effect the shearing of the fastening, and only one of which effects the presenting movement. The fastening shearing and presenting movements are accomplished by rotation of the fastening receiving means in a single direction and means having a powerful leverage is provided to effect or assist in overcoming the high resistance during the fastening severing movement, and means having less leverage and a greater throw is provided to continue the movement under lessened resistance to present the severed fastening in driving position.

Other features of the invention comprise novel means for setting the dies accurately in position and novel construction of the dies to facilitate adjustment and renewal.

These and other features of the invention will appear more fully from the following detailed description when read in connection with the accompanying drawings and will be pointed out in the appended claims.

In the drawing:

Fig. 1 is a front elevation, partly in section, of mechanism embodying the invention: 85

Fig. 2 is a side elevation of part of the mechanism shown in Fig. 1 as viewed from the left of that figure;

Fig. 3 is a side elevation, viewed from the right in Fig. 1, of the fixed shearing die 90 and its supporting mechanism;

Fig. 4 is a side elevation, viewed from the

right in Fig. 1 and on an enlarged scale, of the movable shearing die; and

Fig. 5 is a sectional view, on a larger scale, of the wire shearing dies and their supporting mechanism shown in Fig. 1.

In the illustrated form of the invention, the wire feed mechanism is situated at the left-hand side of the machine (viewing the machine from the front) and the wire passes from the source of supply at the top of the machine to the said feeding mechanism, which comprises a wire feed wheel 2 (Figs. 1 and 2) rotatably mounted on a horizontal shaft 4 extending from front to rear of the machine, and fixed in a bracket 6 bolted to the head of the machine. The peripheral face of the feed wheel 2 has formed on it ratchet teeth which are engaged by pawls 8, 8 carried by an arm 10 pivotally mounted on the shaft 4. The pawls 8, 8 are held in engagement with the ratchet teeth by springs 12, 12 fixed to the pawl carrying arm 10. The arm 10 is oscillated to rotate the feed wheel by a link 14 connected at its lower end to the arm 10 and at its upper end to one arm 16 of a cam lever pivoted at 18 on the head of the machine. A second arm 20 of the lever carries a cam roll 22 which is held by a spring 24 in engagement with a cam 26 fixed on the driving shaft 28 of the machine. The pawl arm 10 is positively operated by the cam 26 to feed the wire and is returned by the spring 24. The length of wire fed is varied by varying the amount of the return movement and for this purpose the cam lever 16, 20 has a third arm 30 which, when the lever is returned by its spring, engages an adjustable stop cam 32 mounted for convenient rotation on the machine frame.

The wire is held against the feed wheel 2 by a presser roll 34 which is rotatably mounted by a pin 35 on an arm 36 pivoted at 38 to the bracket 6 and is urged toward the feed wheel 2 by a spring 40 surrounding a rod 42 having at its lower end a hole loosely engaging the pin 35 of the roll 34 and passing upwardly through an open slot 44 in the shaft 4 on which the feed wheel 2 is mounted. The spring 40 is confined between a washer 48 seated in a recess formed on the upper face of the shaft and a wing-nut 50 threaded on to the upper end of the rod 42.

A wire shearing die 52, 54 (Fig. 5) is clamped by a screw 56 in one arm of a lever 58, 60, in which is formed a wire guiding groove 62, the lever being pivoted to the bracket 6 on a horizontal shaft 64. The die carrying end of the arm 58 is supported by an eccentric portion 66 (Figs. 1 and 3) of a shaft 68 rotatably mounted in bearings 70, 72 on the bracket 6 and is held against the eccentric portion 66 by a plunger 74 mounted in the bracket 6. The plunger 74 has formed at its upper end an inclined face

76 which is engaged by an inclined face formed on a spring plunger 78 at right angles to the plunger 74. If the plunger 74 is raised so far that the inclined faces become disengaged the plunger 74 may be pulled down by a pin 80 extending through a slot 82 in the bracket 6. The pin 80 prevents rotation of the plunger 74 and a pin 84 prevents rotation of the spring plunger 78. By rotating the eccentric shaft 68 the shearing die may be adjusted vertically about the axis of the shaft 64 on which the arm 58 is mounted. The eccentric shaft 68 has formed on its flanges 86, 86 (Fig. 3) between which the end of the arm 58 is positioned laterally, and there is sufficient clearance between the outer faces of the flanges and the inner faces of the bearings 70, 72 to allow adjustment of the arm and die laterally. To effect this adjustment the shaft 68 is moved axially between the bearings 70, 72 in the bracket 6 and held by a draw bolt 90. Extending on the opposite side of the shaft 64 is the second arm 60 of the die carrying lever (Fig. 1) which, when the lever is turned in a counter-clockwise direction about its pivot shaft 64 as will herein-after be described, engages a screw 94 threaded through the arm 36 and moves the roll 34 away from the wire feed wheel 2, thereby releasing the wire and stopping the feed.

A second shearing die 96, 98 (Fig. 4) is fixed in a block 100 held by screws 99 to the enlarged end 101 of a horizontal shaft 102 extending from front to rear of the machine. The shaft is rotatably mounted in a bushing fixed in the frame. The block 100 has formed in it an open sided, part cylindrical recess 104 in which the die 96, 98 is clamped by a plate 106 having inclined faces 108, 110 which engage the block and die. A screw 112 clamps the plate and block together and, by loosening this screw sufficiently, the die may readily be removed. Each of the shearing dies is made in two parts, 52, 54, and 96, 98. The part 52 has formed in it a wire receiving passage 114 (Fig. 5) which is tapered from its wire receiving end toward its shearing end, there being at this end of the die a parallel portion some quarter of an inch long. This construction allows the wire to pass readily through the die. The part 52 has projecting from it a pin 116 which enters a saw-slot 118 in the arm 58 to prevent the part from rotating. The part 54 (Fig. 3) against which the wire is sheared is a readily replaceable, part cylindrical block. The part 96 (Fig. 4) in the block 100, which effects the shearing of the wire, is a block similar in shape to the part 54 and has fixed in it a pin 120 (Fig. 5) which enters a groove 122 in the block 100 to prevent the part 96 from rotating. The part 98 has formed in it a groove or channel 124 to receive the end of the wire which is to be

sheared off to form the fastening. During each cycle of the machine the shaft 102 is oscillated through ninety degrees to carry the die 96, 98 from a horizontal position in which it receives the end of the wire to a vertical position in which the slug is driven into the work, and during this movement the wire is sheared, the die being returned to its horizontal position after the driving and at the end of the cycle. When in its vertical position, the slug containing passage of the die 96, 98 is in alignment with a driver 125 (Fig. 5) constructed and operated in the usual manner. To prevent the severed fastening from falling out of the passage 124 when the block 100 is rotated to carry the fastening from shearing position to inserting position, the part 98 has in it a ball 126 which projects slightly into the passage 124. A spring 128 holds the ball in engagement with the severed fastener. The passage in the shearing die 96, 98 is, when the die is in its horizontal position, in line with the passage in the die 52, 54, so that the wire fed through this die enters the passage in the second die. The opposed end faces of the dies are at this time close together and as the die 96, 98 is moved to its vertical position the end of the wire is sheared off to form the slug.

To enable the operator readily and accurately to set the shearing dies in the lever 60 and block 100, the lever 58, 60 (Fig. 1) may be removed from its operative position and fulcrumed on a pin 130 fixed in the bracket 6 with its face, which normally rests on the eccentric 66, supported by a stud 132 projecting from a block 134 fixed on the bracket 6. The end of the lever 60, in which is the shearing die, is thus positioned adjacent to a gage face 136 formed on the block 134, which face is so arranged that if the die is adjusted in the lever until its outer end engages this face and is clamped in the lever, it will be correctly positioned in the machine when the lever is returned to its operative position. When the lever is returned to its operative position, the die 96, 98 in the block 100 may then be set up to the die in the lever and clamped in position. The die 96, 98 will then, when rotated to present the slug in driving position, have proper clearing relation to an abutment 127 against which the work is presented. To enable the lever 58, 60 to be readily withdrawn, the nut 50 is slackened and the rod 42 removed from the open slot 44 in the shaft 4; this allows the arm 36 to swing downwardly out of the way. The shaft 64 is then withdrawn and the lever removed. To enable the shaft 64 to be withdrawn it is provided with a knurled head 138 (Fig. 2) and is held in position by a spring plunger 140 in the bracket 6 which engages a groove 142 on the shaft 64.

Should a slug be not fully driven in the

work and its upper end project into the shearing die 96, 98, this die will, in some cases, during its return movement, pull out the slug and carry it back with it. When this happens the slug will engage the shearing die 52, 54 or arm 58 and will raise that die and arm against the action of the spring plunger 78 and will cause the arm 60 of the lever 58, 60 to engage the adjusting screw 94 on the arm 36 and lower the presser roll 34 away from the wire feed wheel 2. Damage to the mechanism is thus prevented and if the machine is again started the wire feed is cut out until the slug is removed. Of course, any solid material, such as a piece of broken driver, or slug material, or any other obstruction projecting from either die, will produce a like result.

Fixed on the shaft 102 (Fig. 1) is an arm 146 to which is pivotally connected at 147 the lower end of a link 148 the upper end of which encircles an eccentric 150 on a horizontal shaft 152 rotatably mounted in bearings on the frame above and parallel to the shaft 102. Fixed on the shaft 152 at each side of the eccentric 150 are two pinions 154 which mesh with gear segments 156 formed on a cam lever 158 pivoted at 159 to the frame. The cam lever 158 has a cam roll 160 which enters a cam groove 162 formed in a cam 164 fixed on the main shaft 28 of the machine. By this mechanism the shaft 102 is moved through ninety degrees to shear the wire and carry the severed slug to driving position, and since it is important that the die shall be accurately located both in its horizontal position, in which it receives the wire, and in its vertical position, in which the driver passes through the passage in the die to drive the slug, the mechanism is so arranged that the center 166 of the eccentric 150, the axis of the shaft 152 on which it is fixed and the pivotal point 147 of the lower end of the eccentric link 148 and arm 146 are substantially in line at each limiting position of the die 96, 98. By this means any slackness between the teeth of the segments and pinions has very little, if any, effect upon the position of the die.

To relieve the teeth of the segments and gears of strain during the shearing of the wire, a cam lever 170 is rotatably mounted on the die carrying shaft 102 and this cam lever has a roll 172 which enters a cam groove 174 formed on a cam fixed on the main shaft 28 of the machine. The cam lever 170 has formed on it a lug 178 which, during the shearing action, engages a lug 180 formed on the arm 146 which, as stated, is fixed on the die shaft 102. The cam tracks 162, 174 are so formed that during the shearing the die shaft 102 is driven by both cams but the strain due to the shearing is taken by the second cam lever 170 through the engaging faces of the lugs 178, 180, and after

the shearing of the wire these faces part company and the die shaft 102 is moved to the position in which the slug is driven by the first cam 164 through the segments 156 and pinions 154. The cam roll 172 on the cam lever 170 is mounted on an eccentric stud fixed in the lever so that the roll may be adjusted properly to position the face of the lug 178 on the lever in relation to the face of the lug 180 on the arm 146.

Having thus described my invention, what I claim as new and desire to secure by Letters Patent of the United States is:

1. In a fastening inserting machine, the combination of fastening receiving means, means for feeding fastenings to the receiving means, fastening inserting means, and means becoming operative upon failure of the inserting means properly to insert a fastening for rendering the feeding means inoperative.

2. In a fastening inserting machine, the combination of means for feeding continuous fastening material, means for severing and presenting a portion of the material in position to be driven into the work, driving means, and means for rendering the fastening feeding means inoperative in case a portion of the material remains in the presenting means upon its return from presenting position.

3. In a fastening inserting machine, means for feeding continuous material, means for receiving a portion of the material and movable to sever the portion and present it in position to be driven into the work, a driver for inserting the severed portion, and means operated in case the driver breaks and projects from the presenting means to render the feeding means inoperative.

4. In a fastening inserting machine, the combination of fastening receiving means having fastening shearing and presenting movements, and two actuating mechanisms arranged to operate in conjunction to effect the shearing of the fastening and one mechanism only acting to effect the presenting movement.

5. In a fastening inserting machine, the combination of means for feeding continuous fastening material, cooperating dies to which the material is fed, means for moving one die to sever and present a portion of the material in position to be driven into the work, driving means, and means operated by movement of the other die for rendering the fastening feeding means inoperative in case a portion of the material remains in the first die upon its return from presenting position.

6. In a fastening inserting machine, means for feeding continuous material, co-operating dies having alined passages for receiving a portion of the material and relatively movable to sever the portion and present it in position to be driven into the work, a driver

for inserting the severed portion, and means operated by movement of one die transmitted to the other die to render the feeding means inoperative.

7. In a slugging machine, the combination of a driver, a device for transferring slugs to the driver, and means detecting the presence of an obstruction in said device after the action of the driver and acting to render the machine functionally inoperative without injury to the machine.

8. In a slugging machine, slug wire feeding mechanism, a movable shearing and slug transferring die, a co-operating die, and connections from said co-operating die for rendering the feeding mechanism inoperative in case the co-operating die is moved by the transferring die because of an ineffectual slug inserting operation.

9. In a slugging machine, slug transferring means, a shearing die, means for moving the transferring means relatively to the die to transfer the slug, said die being mounted to yield in the direction in which the transferring means moves on its return from slug transferring movement, and means responsive to said yielding movement to render the machine inoperative to insert slugs.

10. In a machine for severing and inserting fastenings, the combination of a pair of dies relatively movable to sever a fastening from a strip of fastening material, one of said dies being also movable to transfer the severed fastening to inserting position, and mechanism operating under comparatively high power for causing comparatively slow relative movement of the dies during the severing operation and operating under lower power to move one of the dies at a substantially higher speed during the transferring.

11. In a machine for severing and inserting fastenings, the combination of a pair of relatively movable dies arranged to sever a fastening from a strip of fastening material and to transfer the severed fastening to inserting position, and mechanism operating under comparatively high power for causing comparatively slow movement of one of the dies during the severing operation and operating under lower power to move said die at a substantially higher speed during the transferring movement.

12. In a slugging machine co-operating dies one of which is movable to sever a slug and thereafter to transfer the slug to driving position by continued movement in the same direction, and a plurality of operating mechanisms for said movable die operating at different times according to whether the heavy duty of slug shearing or the lesser duty of slug transferring is required.

13. In a fastening inserting machine, the combination of fastening receiving means

comprising dies having relative movement to shear off and present a fastening, and two die propelling mechanisms arranged to operate in conjunction to effect said relative movement to shear off the fastening and one only of said mechanisms continuing said movement to present the fastening in driving position.

14. In a machine for forming and inserting fastenings, the combination of fastening receiving dies, one die having fastening shearing and presenting movements, operating means having long leverage and a short throw for effecting initial movement of the movable die to sever the fastening, and means having short leverage and a longer throw for effecting the final movement of the die to present the fastening in position to be driven.

15. In a fastening forming and inserting machine, the combination of fastening inserting means, a relatively fixed die, a die arranged for rotation to sever a fastening and by continued movement in the same direction to present the fastening in driving position, and two die rotating mechanisms operating in conjunction to effect the fastening severing movement of the rotatable die, one of said mechanisms operating to continue rotation of the die to present the fastening in driving position.

16. In a machine for forming and inserting fastenings, the combination of fastening receiving means having fastening shearing and presenting movements, operating means having long leverage and a short throw for effecting the shearing movement, and means having short leverage and a longer throw for effecting the presenting movement.

17. In a fastening forming and inserting machine, the combination of fastening receiving means arranged for rotation to sever a fastening and by continued movement in the same direction to present the fastening in driving position, and two driving mechanisms operating in conjunction to effect the initial movement of the rotatable means, one of said mechanisms operating to continue movement of the rotatable means to present the fastening in driving position.

18. In a slugging machine, co-operating dies one of which is movable initially to sever a slug and finally to transfer the slug to driving position, and two operating mechanisms for said movable die, one adapted to effect the initial movement of the die and the other to effect the final movement.

19. In a slugging machine, co-operating dies relatively movable to shear off the slug material, each die comprising a portion having a groove for the slug material and a portion having a flat face covering the groove, the dies being oppositely disposed so that upon relative movement shearing of the slug

material is effected by the portions having the flat faces, and means for causing relative movement of said dies.

20. In a slugging machine co-operating dies, each cylindrical as a whole and each comprising a part having a groove or channel for the slug material and a part having a flat face covering the channel.

21. In a slugging machine, a die cylindrical in form and split longitudinally in a plane at one side of its axis, the larger part having a groove for the slug material.

22. In a slugging machine, a cylindrical die, a die holder having a recess embracing more than half the circumference of the die, and a clamp arranged to engage a surface of the die not in the holder.

23. In a slugging machine, a fixed stud on the machine, a die, a die carrier having a hole to receive the stud, and a gage plate against which the die is positioned to locate the die in the carrier in predetermined relation to said stud.

24. In a slugging machine, a die carrier pivoted to the frame, a rest for the carrier, a spring plunger for holding the carrier against the rest, and means for adjusting the carrier in the direction of action of the plunger.

25. In a slugging machine, a die, a die carrier, a co-operating die, said die carrier being pivoted to the frame for adjustment relatively to the co-operating die, and means for adjusting the die carrier comprising a rotatable and longitudinally movable eccentric shaft having flanges to prevent relative movement of the carrier and shaft longitudinally of the shaft.

26. In a slugging machine, a die, a die carrier arranged for rotation to move the die from a horizontal slug receiving position to a vertical slug driving position, an arm on the carrier, an eccentric strap pivoted to the arm, an eccentric, and a pinion connected to the eccentric, said parts being so constructed and arranged that in the limiting position of the die the center of the eccentric, the axis of the pinion and the pivot of the arm are in alinement.

27. A fastening inserting machine having means arranged to feed a strip of fastening material toward fastening inserting location, a die past which fastening material is fed by the feeding means, a second die arranged to receive a fastening length of the fastening material as it is fed past the first die, means arranged to hold the first die stationary during normal operation of the machine constructed to permit that die to yield if hit by an obstruction projecting from the second die, and means arranged to rotate the second die to cause the dies to sever a fastening from the fastening stock and to cause the second die to carry the fastening thus severed into the line of drive.

28. A fastening inserting machine having a shaft, means for rotating said shaft, a die carried by the shaft having a fastening receiving passage arranged to be rotated from fastening receiving to driving position by rotation of the shaft, a second die having a fastening material receiving passage in alinement with the passage of the first die when the latter is in fastening receiving position, means for feeding a strip of fastening material to the dies, and connections from one of said dies to said feeding means arranged to render said feeding means inoperative if an obstruction projects from one of the dies. In testimony whereof I have signed my name to this specification.

WILLIAM THOMAS BUCKINGHAM ROBERTS.
